UNITED STATES PATENT OFFICE.

SIEGMUND SAND AND ALOIS A. RITTER, OF RACINE, WISCONSIN, ASSIGNEES TO HARTMANN TRUNK COMPANY, OF RACINE, WISCONSIN, A CORPORATION OF WIS-CONSIN.

DESIGN FOR A WARDROBE TRUNK.

Application filed February 4, 1929. Serial No. 29,940. Term of patent 14 years.

To all whom it may concern:

Be it known that we, SIEGMUND SAND and ALOIS A. RITTER, citizens of the United States, residing at Racine, in the county of Racine and State of Wisconsin, have invented a new, original and ornamental Design for Wardrobe Trunks, of which the following is a specification, reference being had to the accompanying drawing forming part thereof.

In the drawing Fig. 1 is a perspective view of the wardrobe trunk, showing our new design; Fig. 2 is a view of the opposite side of the trunk, and Fig. 3 is a view of the lower end of the trunk.

We claim:

The ornamental design for a wardrobe trunk, as shown.

SIEGMUND SAND.
